TOBACCO CONTAINER

William S. Luckett, New York, N. Y.

Application March 3, 1937, Serial No. 128,752

4 Claims. (Cl. 229—27)

This invention relates to improvements in tobacco containers.

Its object is to provide a simple and inexpensive device which may effectively serve as a carton or package for holding and preserving its contents, and which may be carried as a pouch from which the tobacco may be dipped or poured conveniently.

More specifically, its object is to provide a carton which forms a tight package when closed and which is provided with fold lines which enable the user to spread its top open into a form which give easy access to the contents and at the same time forms a spout or spouts through which the contents may be poured.

These and other objects of the invention will appear in the following specification in which several embodiments will be described, and its novel features set forth in claims.

20 Referring to the drawings,

Fig. 1 is a perspective view of a closed container which is made according to my invention;

Fig. 2 is a perspective view of the container shown in Fig. 1, partly opened;

25 Fig. 3 is a perspective view of the same container with its sides spread to give access to its contents and illustrating the way tobacco may be dipped from it;

Fig. 4 is a view similar to Fig. 3 with the container tipped into a position to permit its contents to be poured through a spout formed in its sides;

30 Fig. 5 is a front elevation of a carton showing a modification of the fold lines in the side thereof;

Fig. 6 is a plan view of a blank from which the container shown in the preceding figures is formed;

Fig. 7 is a view similar to Fig. 2 illustrating 35 a modification of the fold lines and also a different form of edge tabs;

Fig. 8 is a portion of a blank like that shown in Fig. 6 illustrating a novel manner of attaching a band or strap;

40 Fig. 9 is an illustration of a container like that shown in Fig. 1 with a protective cover;

Another development of the invention is shown in the remaining figures, of which Fig. 10 is a view similar to Fig. 9 of a duplex container 45 and a protective cover therefor;

Fig. 11 is a plan view of a blank from which the duplex container shown in Fig. 10 is formed; and

Fig. 12 is a perspective view of the duplex container shown in Fig. 10, with its two parts moved

into a substantially parallel relation and with one of them open.

The blank shown in Fig. 6 is cut from a relatively stiff material and creased or scored to be folded on the lines 10, 11, 12, 13, 14 and 15, 5 into a rectangular carton in the usual manner. The parts between lines 10 and 11 and between lines 12 and 13 form the sides 20 and 21 of the carton; the parts between lines 11 and 12 form one of its edges 22, and the parts outside of 10 lines 10 and 13, which are preferably stuck together, form its other edge 23. The parts below the line 14 are folded inwardly and stuck together to form the bottom 24. The upper parts of the blank between lines 10, 11 and 12, 15 13 then form the front flap 25 and the rear flap 26. So far there is no novelty in the construction of the carton.

I prefer to make the edge tabs 27, 28 continuations of both of the sides 23, 22, and the front 20 flap 25, with fold lines 29, 29 between them and diagonal fold lines 30, 30 across the tabs. These then fold in when the front flap is closed, as shown in Fig. 2, and form a tight closure. In Fig. 7 the edge tabs 27A and 28A are shown as 25 continuations of only the front flap 25. They may also be made as continuations of the edges 22 and 23 in the usual manner, but I prefer to make them as shown in Figs. 2, 3, 4 and 6, because they form a tighter package. 30

An important feature of my invention is to provide diagonal fold lines 31, 32 from the lower corners of the sides 20, 21, converging to the center of the upper edges of the sides, and transverse fold lines 33, 33 across the center of the 35 flaps 25, 26.

The fold lines need not be diagonal or converging. In Fig. 5 I have shown them at 31A as parallel.

As a convenient way of holding the carton 40 closed, I have shown a strap 40 which may be in the form of an elastic band, riveted or otherwise fastened, such as is shown in Fig. 8, to the bottom of the carton, as at 41, with a washer 42 of fiber. This may be drawn around the closed 45 carton, as shown in Fig. 1, and its end secured to the washer or tucked under the attached end of the strap.

Another way of attaching the strap 40 to the carton is shown in Fig. 8. In this case the part 50 of the blank which forms the outer flap of the bottom is provided with a rectangular slot from the outer edge of the flap to its center. A loop of the endless elastic band or strap 40 is passed through this slot before this flap is folded 55

against and glued to the flap which it overlaps. The band is thus securely attached to the package without the possibility of any part of it coming in contact with the contents.

5 In use the flaps and edge tabs are raised. In Fig. 2 the rear flap 26 is fully raised and the front flap 25 and consequently the edge tabs partially raised. When both flaps and both tabs are raised, a pressure of the fingers on the 10 upper part of the edges will move them toward each other. This causes the sides to bulge at the top, bending on the fold lines 31, 32 and the flaps to bend on the fold lines 33.

The package will then be in the form shown 15 in Figs. 3 and 4. Fig. 3 shows the accessibility of the contents when the carton is thus distorted, and the ease with which its contents, if it be smoking tobacco, may be dipped out or scooped up into a pipe P. Fig. 4 shows the carton tilted to 20 pour tobacco into the pipe P through a spout formed by the bend in the flap 25.

The carton or box thus described is preferably made of a material which is dampproof or, at 25 least, dampproofed on its inner surfaces. This does away with the need of an inner wrapper which so easily becomes wrinkled and torn after it is once opened. Such a wrapper, furthermore, interferes with access to the contents of the package and would make pouring from it difficult.

30 The closed package may be wrapped in a damp-proof material in the usual way. If desired, an outer slip cover 50, open at both ends, as shown in Fig. 9, may be provided or one open at one end only, as shown at 50A in Fig. 10, which has a back 51 may be used if preferred. In this case the strap 40 is not necessary.

In the modification shown in Fig. 7 the fold lines 31A, 32A run from the lower corners of the sides to the center of the outer edges of the 40 flaps 25, 26. The operation of this form is similar to that already described.

The duplex package shown in Figs. 10, 11 and 12 is made of a blank shown in Fig. 11. When this is folded together it forms two boxes 60, 61 interconnected at a fold line 62. This is cut out at 63 to facilitate the use of the packages. Each of them is similar to the box shown in the preceding figures, except that it has no rear flap, and the front flaps 65 are extended to form auxiliary flaps 66 which may be tucked down into the package to cover the cut-out parts 63 and to more completely cover the package.

In Fig. 12 the boxes 60, 61 are shown side by side with the flap and tabs of one of them opened. 55 By opening both flaps, both boxes may be filled, their flaps and tabs closed and then swung into alignment, as shown in Fig. 10. Then they may be wrapped or put into the cover 50A.

The advantage of this arrangement is that the two boxes may be torn apart along the fold line 62, which may be perforated if desired, forming two handy pocket size packages. Each of them has the fold lines 31, 32, as in the formerly described case, and the fold lines 33 are continued across the flaps 65 and the auxiliary flaps 66.

Other modifications than those shown and described may be made within the spirit and scope of this invention and, of course, this container may be used for packaging cigarettes or any desired material. I intend no limitations other than those imposed by the appended claims.

What I claim is:

1. A carton of rectangular cross section having sides and edges, both of said sides being extended upwardly to form flaps adapted to be folded over the top of the carton, tabs integral with the edges and with one of the flaps, diagonal fold 20 lines across the tabs, fold lines from the lower corners of the sides converging to the center of their upper edge, to cause said sides to bulge outwardly at the top when the upper edges of the carton are moved toward each other to form 25 a pouring spout, and fold lines across the flaps.

2. A pair of cartons folded from a single blank, each having sides and edges and a flap, the part of the blank which forms adjacent sides of both cartons being continuous, and fold lines in the 30 sides of the cartons to cause said sides to bulge outwardly at the top when the upper edges of the sides are moved toward each other to form pouring spouts.

3. A pair of cartons folded from a single blank, 35 each having sides and edges and a flap, the part of the blank which forms adjacent sides of both cartons being continuous and having a transverse fold line therein, and fold lines in the sides of the cartons from the ends of one of their edges 40 converging toward their opposite edges to cause said sides to bulge outwardly at the top when the upper edges of the sides are moved toward each other to form 45 pouring spouts.

4. A pair of cartons folded from a single blank, 45 each having sides and edges and a flap, the part of the blank which forms adjacent sides of both cartons being continuous and having a transverse fold line therein, and fold lines in the sides of the cartons from the ends of one of their edges 50 converging to points intermediate the ends of their opposite edges to cause said sides to bulge outwardly at the top when the upper edges of the sides are moved toward each other to form 55 pouring spouts, and fold lines across the flaps.

WILLIAM S. LUCKETT.
